UNITED STATES PATENT OFFICE.

LEVIN D. NOBLE, OF CERRO GORDO, ILLINOIS.

IMPROVEMENT IN DITCHING AND GRADING MACHINES.

Specification forming part of Letters Patent No. 137,218, dated April 1, 1873; application filed August 5, 1872.

To all whom it may concern:

Be it known that I, LEVIN D. NOBLE, of Cerro Gordo, in the county of Piatt and State of Illinois, have invented certain Improvements in Ditching and Grading Machines, of which the following is a specification:

This invention consists in certain novel peculiarities of construction and arrangement for purposes of facilitating the proper manipulation of the machine, which are fully explained in the ensuing description and specifically pointed out in the claims.

Figure 1 is a perspective view of my improved ditching and grading machine. Fig. 2 is an elevation of the ditcher or excavator part of the machine seen from the land-side. Figs. 3, 4, and 5 are detail views of different parts of the machine.

The same letters of reference are employed in all the figures in the designation of identical parts.

The excavations are made by the share A, which is fastened in any approved manner to a standard of the beam B, said standard being also used for the support, in part, of the land-side C. The beam is provided with the ordinary rotary colter D and the swiveling-wheel E, which may be raised or lowered through the medium of the lever F, which turns on a fulcrum on the standard f carried on top of the beam. The slice of earth cut off by the share is thrown upon the side of the ditch by the long inclined mold-board G, which forms a continuation of the share, being suitably secured and braced to the standard and land-side of the plow. The excavator is supported by an additional caster-wheel, H, which runs upon the bank furthest from the land-side, being attached flexibly to the beam by means of suitable links H', and controlled by a lever, I, which is pivoted to the vertical shank of the frame which supports the wheel, and, extending thence to the rear, is fulcrumed upon a standard, i, on the mold-board, as best seen in Fig. 1. The special function of this additional wheel H is to hold the excavator in an upright position, it being successively elevated each time it becomes necessary to lower the plow for the purpose of deepening the ditch by means of the lever I. The earth thrown upon the bank by the mold-board is spread or car-

ried away from the ditch by the scraper K, which runs on the bank behind the mold-board, and is arranged obliquely to the line of draft, as shown. It is flexibly connected to the land-side C by jointed and extensible arms L, differing in length, so as to hold the scraper in the desired obliquity with reference to the land-side. The arms L may be constructed as shown in Figs. 3 and 4; but I prefer to use such as are illustrated in detail in Fig. 5, which give flexibility to the scraper also in the direction of its length, so that it may accommodate itself to inequalities of surface, besides permitting of adjustment of its pitch. Each such arm consists, essentially, of four bars, l l' l'' l''. The first one, l, is at one end suitably connected to the land-side by a joint, and pivoted by a horizontal pintle, 1, to ears 2 2 of the second bar l', the other end of which laps in whole or in part the third bar, l'', and is adjustably attached thereto, so that the arm may be shortened or lengthened in this part. The last bar l'' is connected by a vertical hinge to the back of the scraper, and pivoted to the end of the bar l''. It extends, however, beyond this pivotal point, and terminates in a cross-head, 3, having a curved slot in it, through which a clamping-screw passes into the bar l'' for clamping the bars l'' and l''' firmly together when the scraper has been set at the desired pitch.

The draft is transmitted to the scraper K by a chain, K', connecting the forward end of the scraper to the back of the mold-board. To guide the excavator in widening the ditch, two guide-wheels, M and M', are employed, which are suitably secured to the standard and braces of the plow, and project beyond the land-side so as to run along the vertical side of the ditch. These guide-wheels are adjustably connected to the standard and braces, so that the distance which they shall project from the land-side C may readily be regulated, and each is provided with a sharp flange, m, to cut into the earth, enabling the guide-wheels to support the plow above the bottom of the ditch. A second scraper, N, may be employed to carry the excavated earth still further away from the ditch. When used it is hitched by chains to the excavator and first scraper K in the manner clearly illustrated in Fig. 1. Its arms L are connected by a bar, L¹, and a diagonal

bar, L^2 , and each carries at its outer end a guide-wheel constructed in every respect like the guide-wheels M and M' , running against the opposite side of the ditch, as shown in Fig. 5, to hold the scraper in proper position in relation to the scraper K . This second scraper is provided with a caster-wheel, O , fastened to a lever, P , and it may be used separately.

What I claim as my invention, and desire to secure by Letters Patent, is—

1. In combination with the excavator, the supplemental adjustable caster-wheel H arranged to run upon the bank, substantially as and for the purpose specified.
2. In combination with the excavator, the

guide-wheels M M' , substantially as and for the purpose specified.

3. The guide-wheels M M' having sharp flanges m , in combination with the excavator, substantially as and for the purpose specified.

4. The combination of the scraper and jointed extensible arms L , which are composed of the parts l^1 , l^2 , 2 , l^3 , and l^4 , substantially as and for the purposes specified.

In testimony whereof I have signed my name to this specification in the presence of two subscribing witnesses.
